COMPRESSOR

William W. Wishart, Chicago, Ill.

Application January 23, 1935, Serial No. 3,030

10 Claims. (Cl. 230—140)

My invention relates in general to fluid flow apparatus and has particular reference to rotary fluid flow devices and more especially devices adapted for use as pumps or compressors, the 5 same comprising additions and improvements on the invention disclosed in my co-pending application, Serial Number 743,196, filed September 8, 1934.

An important object of the invention is to provide a rotary fluid flow device having an entrance and an exit for a work medium and means whereby flow may take place through the device from the entrance to the exit regardless of the direction of rotation of the device.

Another important object is to provide a device of the class described having means whereby work material, admitted through the entrance, travels thence through a channel terminating in a forked duct having arms extending on opposite sides of the work blade and opening each into the work space on opposite sides of the blade; a further object being to form the channel, through which the work medium is delivered to the forked duct, in a shaft, on which one of the co-operating elements is carried.

A still further important object is to form the forked duct in a wall of the cylinder element.

Another object is to provide sealing means between the members containing the communicating ends of the duct and channel; a further object being to mount the sealing means on the element containing the channel in position to form sealing engagement with the surface of the cylinder wall in which the communicating end of the duct opens.

A further important object is to form the seal as an annular element carried by the part in which the channel is formed and axially movable thereon to a position engaging the facing surface 40 of the cylinder wall containing the duct; a still further object being to mount the seal in such a way that, during the operation of the device, the seal wipes against a surface of the cylinder of larger area than the contacting surface of the 45 seal, to the end that wearing of the cylinder surface by the seal is reduced and the seal laps or polishes the cylinder surface on which it seats and thus maintains said surface in smooth condition for effective sealing.

A further object is to form the annular wall of the cylinder with longitudinal channels positioned to communicate with the arms of the forked duct and to provide bores between said channels and the inner face of the annular cylinder wall in order to provide inlet ports to the work

space within the cylinder, a still further object being to mount the inwardly opening inlet valves in said bores so as to minimize the pocket space between the valve and work space as much as possible.

Another important object is to provide an inwardly opening valve for the inlet ports of such construction that pocket space between the valve and the work space is entirely eliminated; the valve, when closed, forming a substantial continuation of the inner face of the annular wall of the cylinder.

A further important object is to provide a device of the character described, in which the blade is fixed on the cylinder in position extending inwardly of the annular wall thereof and clamped at its opposite ends between the end walls of the cylinder and in which the piston is formed with a slot for receiving the blade, the opposite sides of the slot being formed to rockingly receive the bearing blocks and the yielding means for forcing the same against the blade.

Another important object is to provide suitable lubricating means for all of the operating parts of the device; a further object being to provide a lubricant circulating system including forcing means built into the device and driven in response to the rotation of at least one of the co-operating elements of the device; and a still further object being to form one of the co-operating elements for rotation with a supporting axle and to deliver lubricant from the forcing means through a duct formed in the axle and in the co-operating element thereon, said duct discharging into the cylinder in position to lubricate the working surfaces of the cylinder and piston and being thence returned through suitable conduits to the suction side of the lubricant forcing means.

Another object is to provide for changing the relative eccentricity of the piston and cylinder.

Numerous other objects, advantages, and inherent functions of the invention will be apparent from the following description, which, taken in connection with the accompanying drawings, discloses a selected embodiment of my invention.

Referring to the drawings:

Figures 9 and 10 are, respectively, a longitudinal section through, and an end view of a device embodying my invention, and provided with 15 means for relatively adjusting the working parts; and

Figure 11 is a longitudinal section similar to Figure 1 showing a modified form of the device.

To illustrate my invention, I have shown on 20 the drawings, an hydraulic apparatus more especially adapted to function as a pump or compressor, although it will be obvious that many features of the invention will have general application in hydraulic or fluid flow apparatus 25 other than pumps.

Devices embodying the invention, however, are characterized in that the work medium flows from the inlet or entrance of the device to the outlet or exit regardless of the direction in which 30 the operating parts are moved. The device illustrated comprises a casing 11 having an entrance 13 and an exit 15 for the work medium and means 17, comprising relatively movable co-operating elements including a cylinder 19 and 35 a piston 21 having co-operating working surfaces, at least one of which is adapted to move circularly in either direction during operation of the device and a working blade 23 extending between the cylinder and piston and operatively associated with the working surfaces of both. The invention is particularly adaptable for incorporation in rotary pumps or compressors since the advantage of a pump, which will not reverse fluid flow there through but will deliver the work 40 medium continuously in one direction through the device regardless of the direction in which the rotary part or parts are driven, is obvious.

Despite the manifest advantages of such a pump or compressor, I am unaware that any 50 pump or compressor, capable of functioning in the manner described, has heretofore been provided and, since the invention may, of course, be applied in other types of hydraulic apparatus than the pump or compressor illustrated herein, 55 I do not wish to limit the invention to the specific type of machine illustrated in the drawings. The invention, in fact, may be applied in any type of rotary fluid-flow device and is not necessarily restricted to the illustrated embodiment, 60 in which the piston element and cylinder element rotate in unison about eccentric axes. On the contrary, the invention may be applied in rotary devices wherein the piston is stationary and the cylinder is rotated, or wherein the cylinder is stationary and the piston rotated within 65 the cylinder, or wherein one of the co-operating elements, either piston or cylinder, is given a relative gyroscopic or orbital movement in a circular path with respect to the other working element with which it cooperates. I contemplate the embodiment of the novel features of my present invention in all of the foregoing well known rotary compressor constructions in a manner which, it is thought, will be obvious from 70 the specific disclosure made herein of the in-

vention as applied in a pump or compressor having the piston 21 and cylinder 19 rotating in unison about relatively eccentric axes.

In the illustrated embodiment, the cylinder and piston are mounted for rotation about relatively parallel eccentric axes with the piston in contact with the inner surface of the cylinder. Since the inner diameter of the cylinder is larger than the external diameter of the piston, a crescent-shaped working space 24 is defined between the co-operating parts, and the relative movement of the parts 19 and 21, during the operation of the device, is such that the work space is caused to travel around the cylinder continuously in one direction, depending, of course, upon the direction in which the parts are moved, so that a work medium, introduced into the work space, during its relative travel past one part of the cylinder, may be discharged from the work space as the same moves past another remote part of the cylinder and thus accomplish the hydraulic function of the device.

The frame or casing 11 provides a closed housing, in which the elements 19 and 21 are mounted for operation. The casing may be of any suitable form, but I prefer to utilize a casing comprising a pair of co-operating parts, one of which is formed with a base 25 and upstanding walls 27 forming a preferably cylindrical compartment open at one end, the other casing part comprises a preferably circular plate 29 adapted to fit upon and close the open end of the cylindrical compartment provided by the walls 27. The walls 27, at the opening of the cylindrical casing, and the cylindrical edges of the plate 29 are preferably formed with an interfitting tongue and groove formation 31 preferably carrying sealing means comprising a gasket 33 therebetween for the purpose of sealing the joint between the cover 29 and the co-operating walls of the casing on which it seats. The parts 27 and 29 may be secured together in any preferred fashion as by means of the studs or bolts 35.

One of the co-operating parts, preferably the cylinder, is provided with means comprising an axle 37 for driving the same, which axle is journaled in the walls of the frame or casing 11, as by means of the anti-friction bearing 39 mounted in a sleeve-like extension 41 formed preferably on the cover 29. The axle 37 extends outwardly of the outer end of the extension 41 through a cover plate 43, in which the shaft is journaled and which is secured to the outer end of the extension as by means of the bolts or studs 45, there being preferably a sealing gasket 47 interposed between the peripheral portions of the plate 43 and the end portions of the extension 41, on which said plate is seated.

The other one of the co-operating parts, preferably the piston, is carried on a support 49, which in turn is mounted on the frame 11. The support 49 preferably comprises a shaft on which the piston is journaled, the shaft having a piston-carrying portion 51 extending within the cylinder and a mounting portion 53, which is carried in a sleeve-like extension 55 on the frame, preferably in the wall 27 of the casing opposite the cover. The central axis of the shaft portions 51, 53 is eccentric with respect to the axis of the axle 37, so that the piston and cylinder are mounted for rotation about eccentric axes within the casing 11 for the purpose of performing their hydraulic function in the manner heretofore described. I prefer also to form the shaft portion 51, on which the piston is carried in such a way 75

that the axis of the portion 51 is slightly displaced with respect to the axis of the shaft portion 53, this displacement, however, being substantially less than the eccentricity of the axis of the shaft portion 53 with respect to the axle 37. By means of this arrangement, I am able to accurately adjust the eccentricity of the piston within the cylinder by simply turning the shaft 49. Consequently the cylinder and piston supporting means need not be exactly located in the frame and the working surfaces of the piston and cylinder may be finished without maintaining extremely accurate limitations upon allowable tolerance during the finishing operation. The cost of manufacture is thus reduced yet the parts may be accurately adjusted for maximum efficiency in operation, it being understood, of course, that for maximum efficiency the piston should contact snugly with the inner surface of the cylinder but without excessive pressure in a radial direction between the parts at the point of contact. The adjustment also may be used to compensate for worn bearings as well as manufacturing inaccuracies. In order to provide for the convenient adjustment of the piston in the cylinder in the manner just described, the shaft portion 53 extends outwardly of the wall 21, through a preferably threaded embossment 57, the projecting end of the shaft being also threaded as at 59 to receive a nut 61 adapted to lock the shaft in adjusted position, the projecting end of the shaft also being formed with a non-circular portion 63 adapted for the reception of a turning instrument, whereby the shaft may be rotated in the sleeve 55 in order to accomplish the adjustment of the piston within the cylinder. I provide a removable cap 67 adapted to be threadedly secured on the boss 57 in order to enclose the outer end of the shaft 53 and protect the same as well as preventing the escape of fluid from the casing between the shaft and the embossment 57.

Relative adjustment of the cylinder and piston may also be accomplished by providing for shifting the cylinder on the frame, while the axle of the piston remains stationary. To this end, as shown in Figures 9 and 10, the central opening of the end plate 75 is made slightly larger than the sleeve-like frame portion 55 and the end plate is formed as at 191 with means bearing directly on the wall 27 of the frame, which likewise is formed with bearing means 193. If desired, a suitable anti-friction device may be applied between the bearing portions 191 and 193. The cover plate 29 is made radially adjustable on the open end of the casing 11, the tongue and groove 33 being formed to permit such adjusting movement. The casing 11 also has portions 195 comprising an annular flange encircling the peripheral edge of the cover 29 and this flange carries preferably threaded adjusting members 197 adapted to engage the peripheral edge of the cover in order to accurately adjust the same on the casing. By manipulating the screws 197, the position of the axle 37 with respect to the piston axis may be accurately adjusted, after which the studs 35 may be tightened to secure the cover in adjusted position.

The necessary adjusting movement of the cover is of course very small and insufficient, as a practical matter, to disturb the alignment of the axle 37 with respect to a motor shaft or similar driving element with which the shaft may be coupled. Where a flexible coupling is employed, no danger whatever, through disturbance of alignment, is encountered.

The constructions for adjusting the clearance of the piston and cylinder are not, of course, necessarily restricted to the particular construction illustrated and may be applied in any rotary device requiring such adjustment.

In the illustrated embodiment, the piston is mounted for rotation on the stationary shaft portion 51, anti-friction bearing means 65 being interposed between the shaft portion 51 and the piston element, which comprises a cylindrical member having a central bore 69, through which the shaft extends. While I have shown my present invention as applied in a rotary compressor, in which both the cylinder and piston are rotated in order to pump the work medium from the inlet 13 to the outlet 15, it will be obvious that the invention may be applied in any arrangement whereby relative movement is imparted to the co-operating parts 19 and 21 in a manner to cause the work space 24 to circulate relatively around the cylinder and I do not, therefore, wish to limit the invention necessarily to a device in which both the cylinder and piston rotate.

I prefer, however, as in the form shown in Figures 1 through 7, to arrange the parts so that the cylinder at least rotates and, to this end, and to simplify the construction and assembly of the cylinder, I form the same as an assembled structure comprising an annular element or ring 71, the opposite ends of which are closed by preferably circular end plates 75 and 13. The end plates and intermediate ring are secured together in any suitable fashion as by means of a plurality of spaced apart and circularly arranged fastening bolts 77, penetrating registering bolt holes in the end plates and intermediate ring at the peripheral edges of the end plates, the bolts being held in place by nuts 79. One of the end plates is secured on the shaft 37, while the other end plate is formed with an axial opening adapted to receive the sleeve-like portion 55, so that said end plate is journaled on said portion, there preferably being an anti-friction bearing 81 provided in the opening of the end plate for rotatably mounting the same on the portion 55. The cylinder also carries the blade 23 extending in a substantially radial direction, said blade having its outer edge snugly received in a notch 85 formed in the inner surface of the cylinder ring 71.

The blade is as wide or slightly wider than the cylinder ring 71, so that when the end plates and ring are clamped together, the opposite edges of the blade will be snugly pressed against the opposite facing surfaces of the end plates and, if desired, said end plates may be provided with grooves for receiving the opposed ends of the blade. In any event, the blade is tightly held by and between the end plates so that leakage of the work medium between the edges of the blade and the contacting surfaces of the end plates and ring 71 is prevented.

The blade extends in a substantially radial slot 87 formed in the piston so that rotation of the cylinder by means of the shaft 37 will cause rotation of the piston through the driving connection of the blade, which is fixed on the cylinder and has bearing engagement with the piston in the slot 87. It will be seen, therefore, that rotation of the cylinder will cause rotation of the piston through the driving connection provided by the blade. It is, of course, within the contemplation of my invention to provide for driving the piston rather than the cylinder, in

which event, the cylinder will be driven through the blade upon rotation imparted to the piston.

In either case, since the cylinder and piston are mounted for rotation about relatively eccentric axes, the work space 24, when the parts are rotated, will be caused to travel relatively around the circumference of the cylinder ring 11. The blade 23, however, travels with the cylinder so that the operation of the parts in the manner described will result in the development of unequal pressures in the work space 24 on opposite sides of the blade 23. For example, if the elements 19 and 21 are rotated in a clockwise direction, viewing Figures 2 and 4, pressure will be relatively reduced in the space 24 on the right hand side of the blade 23 and will be relatively increased on the left hand side of the blade. Conversely, if the rotation is counter-clockwise, pressure will be reduced in the space 24 on the left hand side of the blade 23 and increased on the right hand side.

I have provided inlet ports 99 opening in the chamber 24 on opposite sides of the blade 23, said inlet ports each communicating with the work medium entrance 13. These inlet openings 99 are provided each with a valve 101 adapted to open inwardly so that, upon rotation of the elements in a clockwise direction, viewing Figures 2 and 4, the work medium may be drawn into the work space 24 on the right hand side of the blade 23 and may not enter through the port 99 opening in the chamber on the left hand side of the blade against the pressure there developed by the clockwise rotation of the parts. When the parts rotate in a counter-clockwise direction, however, the consequent reduction in pressure on the left hand side of the blade 23 permits the work material to enter through the inlet 99 opening in the chamber 24 on the left hand side of the blade. The work medium, under such conditions, may not enter the work space on the right hand side of the blade due to the pressure developed there as a result of the counter-clockwise rotation of the parts.

I also provide outlet ports 103 communicating with the work space 24 on opposite sides of the blade 23, which ports are preferably formed in the cylinder ring 11 and open into the chamber provided by the casing 11. Alternately, the ports 103 may be made in the end plates 13 and 15 as may also the inlet ports 99, although I find it more convenient to form the inlet and outlet ports in the ring 11. The outwardly opening ends of the ports 103 are provided with annular inserts 105 forming outwardly facing valve seats adapted to receive flap valves 107 comprising a preferably flexible strip of any suitable material secured in position as by the fastening member 109 in position to overlie the outwardly opening ends of the outlets 103. I may provide guard means 111 for said flap valves. The flap valves are so arranged as to permit the escape of the work medium from the work space 24 on the opposite sides of the blade whenever pressure is increased by the rotation of the parts. When the parts are rotating in a clockwise direction, viewing Figures 2 and 4, the work medium may escape through outlet 103, which opens on the left hand side of the plate, but may not enter through the opening on the right hand side of the blade into the portion of the space 24 where pressure is reduced by clockwise rotation of the parts. Conversely, when the parts are rotating in a counter-clockwise direction, the work medium, under pressure in the chamber 24, may escape through the

outlet 103 on the right hand side of the blade 23, but may not enter the chamber through the opening 103 disposed on the left hand side, since the flap valve, associated with the opening, will prevent ingress of the medium in response to the reduction of the pressure developed in the work space on the left hand side of the blade, due to counter-clockwise rotation of the parts. Consequently, regardless of the direction of rotation of the parts, the work medium will be drawn into the compression space through one or other of the inlet ports 99, will be compressed in the space, and discharged through one or other of the outlet ports 103. Where the device is being driven in a counter-clockwise direction, viewing Figures 2 and 4, the medium will be drawn into the work chamber on the right hand side of the blade and then be forced around the cylinder and discharged through the outlet 103, which opens in the chamber on the left hand side of the blade.

When the parts are driven in a counter-clockwise direction, however, the medium will be drawn into the inlet port 99, which opens on the left side of the blade and be carried thence around the cylinder and discharged through the outlet opening 103, which opens in the work space on the right hand side of the blade.

In order to deliver the work medium from the entrance 13 to the inlet ports 99, I provide a channel or conduit 113 in the wall portions 28, 30 which conduit 113 communicates from the entrance 13 into an annular chamber 115 formed in the wall portions 27 at the sleeve 55, which carries the piston support 49. The piston support also is formed with a longitudinal channel 117, 35 which communicates with the chamber 115 through a radial opening 119. The channel 117 also opens at the inner end of the shaft 49 and communicates with a duct 121 formed in the end plate 13 of the cylinder. The duct 121 extends 40 in the end plate to a point opposite the inner end of the shaft 49 and has an opening 123 to the inner face of the end plate substantially at the center, through which opening the duct communicates with the channel 117. The duct 121 extends substantially radially of the opening 123 45 and has a pair of forked arms 125, which extend substantially to the periphery of the end plate. The arms 125 each have an opening 127 on the inner surface of the end plate in position to register with ducts 129 formed in the ring 11. 50 These ducts preferably extend longitudinally in said ring and open inwardly to provide the inlet ports 99.

The inlet ports 99 are preferably formed by openings 131 extending in a radial direction through the annular ring 11, said openings extending from the outer to the inner surface of said ring and intercepting the channels 129. The valves 101 preferably comprise spring blades 133, 60 secured in a depression 134 formed in the inner surface of the cylinder ring 11 in position overlying the inner end of the duct 121, which is preferably provided with a sleeve-like bushing 136 forming a valve seat. The outer end of each of the openings 131 may be closed as by means of a plug 138.

As shown in Figure 4 of the drawings, the valves 101 and 107 may comprise leaf springs supported in each in position to close the port with which the same is associated. As shown in Figure 5, however, the valves may each comprise a headed element engaging in a seat formed in a cage 138 and having a stem extending in and carried by said cage. The stem in each case is preferably 75

resiliently urged to normally keep the head of the valve in its seat. The valves, in the openings 131, however, open inwardly into the work space 24 while the valves in the openings 103 open out. 5 When the valves 101 are closed, however, their heads are substantially flush with the inner surface of the ring 71 so that there are no pockets formed into which the work medium may be compressed and thus reduce the efficiency of the machine. It will be noted also that the valves, when closed, do not interfere in any way with the piston 21.

In order to seal the channel 117 and the duct 121 at their point of communication, it being remembered that the channel 117 is formed in the stationary shaft 49 while the duct 121 is formed in the end plate of the rotating cylinder, I mount a sleeve 137 in the open end of the channel 117, said sleeve projecting outwardly of the end of the shaft in position to carry an annular sealing ring 139. This sealing ring comprises a cup-shaped element adapted to contain a sealing gasket 141 of resilient material adapted to seal the space between the ring 139 and the sleeve 137. The end 15 of the shaft 49 is also provided with a groove 143 adapted to contain a spring 145 in position to compress the gasket 141 and yieldingly urge the ring 139 in an axial direction outwardly on the sleeve 137 into engagement with the face of the end plate 73, around the duct opening 123 so that, when the cylinder 73 is rotating, the ring 139 provides a running seal therewith. It will be noted that the end plate 73 rotates about an axis eccentric with respect to the central axis of the 20 annular ring 139 so that the ring bears upon an area of the end plate considerably larger than the contacting area of the ring. Wear of the end plate at its ring bearing surface is thus eliminated and the relative motion of the seal ring on the end 25 plate provides a wiping effect, whereby the ring continuously laps the surface of the end plates and maintains the sealing surfaces in highly polished condition to prevent leakage of the work medium at the seal.

While, in Figures 1-8 of the drawings, I have shown the inlet channel extending from the entrance 13 through the conduit 113, the channel 117, and thence into the duct 121, it is, of course, within the contemplation of my present invention, as indicated at 142 in Figure 11, to form the entrance on the shaft 37 externally of the casing 11 and to connect the entrance directly with the duct 121 through a channel extending longitudinally in the axle 37 in position to communicate directly with the duct, in which event, the piston-carrying shaft 49 may be solid and the necessity of the sealing ring and associated elements eliminated. The fluid medium delivered from the compression space 24 through one of the outlets 103, depending upon the rotation of the operating parts, is, of course, delivered within the casing 11 in compressed condition regardless of the direction of rotation of the mechanism. The compressed medium may be delivered thence through the exit 15. It will be seen, therefore, that regardless of the direction of rotation of the parts, the work medium will flow through the apparatus from the entrance 13 to the exit 15.

In order to provide for adequately lubricating the operating parts, I prefer to employ circulating means built into the frame or casing 11, and connected to be driven from the axle 37, although, of course, separately driven lubricant

forcing means may also be employed. I have, however, shown a lubricant pump comprising an annular stator 149 held between end plates 151 and mounted within the extension 41 of the casing 11. The stator and end plates are preferably held together and in place in the extension in any suitable fashion as by means of the studs 153 and forming a compression space, in which an annular rotor or fluid-forcing element 155 is mounted for operation. The rotor is splined on the axle 37 10 and has an outer surface relatively eccentric with respect to the inner surface of the stator 149.

In many cases, as for instance, where the device is used as a compressor for a medium, which itself comprises a lubricant, the lubricant forcing pump and circulating system just described may be eliminated. For example, a compressor, used in a refrigerating system, in which methyl chloride is utilized as the refrigerating medium, need not be provided with a lubricating system since a suitable lubricant can be delivered to the device with the refrigerant.

The fluid-forcing means is assembled in the extension 41 on one side of a partition 159, which divides the extension 41 into a lubricant suction chamber 161 and a housing for the lubricant pump and the bearing 39, with the chamber 161 extending between the partition 159 and the cover 43. Suitable seal means 162 is preferably provided to seal the openings in the cover and partition at the places where the shaft extends therethrough. The chamber 161 is connected with the fluid-forcing space within the stator 149 by means of a duct 163 formed through the partition 159 and one of the end plates 151. The lubricant pump is first assembled in the extension 41 and the bearing 39 fitted on the shaft 37. The cover may then be applied to the shaft and bearing. As the cover studs 35 are tightened, the sleeve 41 is drawn onto the bearing 39, which, in turn, is forced along the shaft 37, the frictional resistance causing the shaft and cylinder to be forced toward the right, viewing Figure 1, until the bearings 39 and 81, carrying the rotor therebetween, assume final assembled position. 20

When the axle 37 rotates and drives the rotor 155, the lubricating medium is drawn from the chamber 161 through the duct 163, is compressed in the lubricant forcing means, and delivered through the channel 165 extending radially of the rotor 155 into the axle 37. The compressed lubricant is delivered thence through a longitudinal channel 167 formed in the axle to a duct 169 in the end plate 73. This duct opens in a chamber 171 formed by relieving the inner face of the end plate around the seal ring 139, so that the lubricant under pressure is delivered behind the seal ring and assists in forcing the seal into sealing engagement with the end plate 73 as well as lubricating the same. The chamber 171 communicates with the axle opening 69 of the piston so that the bearings 65 therein may receive adequate lubrication. The chamber 171 also communicates through the ducts 173 with an annular chamber 175 formed within the piston. The opposite side walls of the piston are formed with openings 177, which communicate the chamber 175 with the surfaces of the end plates so that lubricant is delivered to said surfaces for lubricating the working surfaces of the piston which are in engagement with the end plates. The bearing 81 receives its lubrication by seepage of lubricant from the end of the chamber 69 and the sleeve-like support 55 con- 30

tains a duct 178 extending from an end of the chamber 89 to a lubricant outlet 181 formed in the walls of the casing 11.

I prefer to connect the outlet 181 by suitable pipes 183 with a reservoir 185 where, if desired, the lubricant may be cooled. The reservoir has a suction pipe 187 connected with the suction chamber 161 so that when the device is in operation, the lubricant is drawn from the reservoir 185 into the suction chamber 161 and is then delivered under pressure through the forcing pump into the compressor as previously described and is then returned from the compressor to the reservoir 185. Some of the lubricant, of course, escapes from the compressor elements and enters the casing 11. This lubricant will collect in a sump 188 at the bottom of the casing and will drain into the reservoir 185 through a pipe connection 191.

20 Since the blade is fixed with respect to the cylinder to prevent leakage between the edges of the blade and the cylinder, with which they engage, it is obvious that the blade will necessarily have a relatively tilting movement during 25 the operation of the device and I form the opposite sides of the slot 87 with recesses 88 adapted to receive preferably semi-cylindrical bearing blocks 81. The bearing blocks have flat surfaces facing the blade and between which the 30 blade may have reciprocating sliding movement during the operation of the device.

The bearing blocks 81 also may rock within the recesses 88 in order to permit the blade to tilt with respect to the piston during the operation 35 of the device, while at the same time maintaining contact between the flat surfaces of the bearing blocks and the opposite sides of the blade in order to seal against fluid leakage therebetween and around the blade. I also prefer to 40 provide recess extensions 83 in the piston in position behind the bearing blocks 81 and adapted to receive means comprising the blocks 85 and spring means 87, adapted to yieldingly urge the bearing blocks 81 at all times toward the blade 45 83.

It is apparent that, since the piston is driven by the blade, one of the bearing blocks, to-wit, the leading block, will be compressed by and between the blade and the recess, in which it is seated so that a proper seal against leakage will be maintained between the blade and the leading block as a result of the driving force exerted 50 on the piston through said block. The trailing block, however, will not be under compression and it is the function of the pressure means 85 and 87 to maintain the trailing block in sealing engagement with the blade at all times. If the device were rotated in one direction only, it would be necessary to provide the pressure means 85 and 87 in co-operation with the trailing block only but since, in the present invention, the device may be driven in either direction, it is necessary to provide pressure means in conjunction 55 with each block in order to seal the trailing block against the blade no matter in which direction the device is rotating.

It is thought that the invention and numerous of its attendant advantages will be understood from the foregoing description and it is obvious that numerous changes may be made in the form, construction, and arrangement of the several parts of the illustrated apparatus without departing from the spirit or scope of my invention or sacrificing any of its attendant ad-

vantages, the forms herein described being merely for the purpose of illustrating the invention.

Having thus described my invention, what I claim as new and desire to secure by Letters Patent is as follows:

1. A rotary reversible compressor comprising a cylinder element and a piston element within the cylinder element, said piston element having an axis relatively eccentric with respect to the axis of the cylinder element, said elements defining a compression space therebetween, means to rotate the cylinder element about its axis, a blade carried by the cylinder element and having bearing engagement on the piston element, said blade being adapted to sweep through said compression space during an operating cycle of the compressor whereby to force fluid in said compression space, said cylinder element having inlet ports communicating with said compression space, one on each of the opposite sides of said blade, both of said inlet ports being provided with valve means opening toward said space, means forming a common inlet communicating with said inlet ports in advance of said valve means, said cylinder element also being formed with outlet means comprising outlet ports communicating with said compression space one on each of the opposed sides of said blade and opening outwardly of said cylinder through a wall thereof, both of said outlet ports having valve means opening outwardly of said compression space whereby the compressor may deliver a fluid work medium from the inlet through said outlet means regardless of the direction of rotation of said cylinder element.

2. A rotary reversible compressor as set forth in claim 1, wherein the cylinder element comprises a cylindrical rim and an end wall on one side of said rim and wherein the common inlet comprises a forked duct extending in said end wall, and means connecting each of the branches of said forked duct with one of said inlet ports.

3. A rotary reversible compressor as set forth in claim 1, wherein the cylinder element comprises a cylindrical rim, the blade being secured on and extending radially inwardly of said rim, wherein said inlet ports comprise openings on the inner surface of said rim on opposite sides of said blade, and wherein the common inlet comprises a forked duct extending in said end wall and opening each at the edges thereof opposite the rim, including duct means in said rim and connecting each of the arms of the forked duct with one of said inlet ports.

4. A rotary reversible compressor as set forth in claim 1, wherein the cylinder element comprises a cylindrical rim, an end wall on one side of said rim and an axle projecting outwardly of said end wall co-axially with respect to the cylindrical rim and providing means for rotatably mounting the cylinder, the common inlet comprising a duct formed longitudinally in said axle, and means connecting each of said inlet ports with said longitudinally extending axle duct.

5. A rotary reversible compressor as set forth in claim 1, wherein the cylinder element comprises a cylindrical rim, an end wall on one side of said rim and an axle projecting outwardly of said end wall centrally thereof and providing means for rotatably mounting the cylinder, a sleeve-like support in which said axle is mounted and through which it extends, said common inlet comprising a chamber defined in said support around said axle, means to seal the chamber against fluid leakage along the surfaces of said

- shaft, said common inlet and duct means extending in said axle for connecting said chamber with both of said inlet ports.
6. A rotary reversible compressor as set forth in claim 1, wherein the cylinder element comprises a cylindrical rim, an end wall on one side of said rim and an axle projecting outwardly of said end wall centrally thereof and providing means for rotatably mounting the cylinder, a sleeve-like support in which said axle is mounted and through which it extends, said common inlet comprising a chamber defined in said support around said axle, duct means extending longitudinally in said axle and opening in said chamber, and a radial duct in said end wall and communicating with said longitudinally extending duct means centrally of said wall, said radial duct having forked arms, each communicating with one of said inlet ports.
7. A rotary reversible compressor as set forth in claim 1, wherein the valve means at the outlet ports comprise sheet metal strip means anchored on the cylinder element and having free ends overlying the outwardly opening ends of 25 said ports including fittings forming valve seats

for the ends of said strip means, said fittings being set in the outwardly opening ends of the outlet ports.

8. A rotary reversible compressor as set forth in claim 1, wherein certain of the valve means comprises a cage disposed in the port with which the valve means is associated, said cage providing a valve seat, a valve having a head adapted to engage said seat substantially at the inner surface of the cylinder whereby to avoid a pocket in said cylinder in communication with said compression space, and spring means normally urging the head to engage the seat in said cage.

9. A rotary reversible compressor as set forth in claim 1, wherein the cylinder element comprises an outwardly extending axle, and wherein in said common inlet comprises duct means in 15 said axle.

10. A rotary reversible compressor as set forth in claim 1, wherein the piston element is carried upon a shaft extending within the cylinder and having an end disposed opposite an end wall of the cylinder, said common inlet comprising at least in part an axial duct in said shaft.
